UNITED STATES PATENT OFFICE.

HOOPER COYNE, OF BALTIMORE, MARYLAND.

SAFETY-RAZOR.

1,142,310.

Specification of Letters Patent. Patented June 8, 1915.

Application filed October 5, 1914. Serial No. 865,116.

To all whom it may concern:

Be it known that I, HOOPER COYNE, a citizen of the United States, residing at Baltimore, in the State of Maryland, have invented certain new and useful Improvements in Safety-Razors; and I do hereby declare the following to be a full, clear, and exact description of the invention, such as will enable others skilled in the art to which it appertains to make and use the same.

My invention relates to improvements in safety razors, and it is intended to provide a cheap, simple, efficient and durable form of safety razor in which the razor blade is held firmly in place when in use, and in which the parts may be readily assembled and disassembled when it is desired to clean the razor or substitute another blade, or for other purposes.

It is well known that with the safety razors now generally in use, there is more or less trouble and annoyance in taking the razor apart and cleaning up the same and then restoring the same to the original assembled position each time that the razor is used.

The object of my invention is to reduce and simplify the number of these parts, and to facilitate the operation of assembling and disassembling these parts, which will be more fully hereinafter described.

Reference is had to the accompanying drawings in which:—

Figure 1 is a top plan view of the complete razor ready for use; Fig. 2 shows the support for the razor blade, with the blade and its sliding locking piece detached, the razor blade being shown in dotted lines; Fig. 3 is a side elevation of the razor with the parts assembled; Fig. 4 shows a section along the line 4—4 of Fig. 1, and looking in the direction of the arrows; Fig. 5 is an end view as seen from the right of Fig. 1, the parts being shown on a larger scale; Fig. 6 shows a section along the line 6—6 of Fig. 4, and looking in the direction of the arrows, the parts being shown on a larger scale; Fig. 7 shows a similar section along the line 7—7 of Fig. 4, and looking in the direction of the arrows; and Fig. 8 is a detail showing the sliding locking piece for locking the razor blade in place on its support.

A represents the holder or support for the

razor, which is preferably provided with 55 clearance slots *a* to register with the edges of the blade.

B represents the stud that is pressed into the holder and projects through the center of the razor blade, and B' represents the two 60 end studs which are provided with engaging flanges *b* as shown in Figs. 4—7.

C represents the razor blade, which is perforated to permit the passage therethrough of the studs B and B', as shown in Fig. 4. 65

D represents the locking piece which is made of a single piece of metal, shown in Fig. 8, and is provided with inwardly-turned flanges *d*, said flanges having beveled ends *d'* as shown most clearly in Figs. 4 and 8. 70 This locking piece is arch-shaped in cross section, as shown in Figs. 5—7, and the inwardly-turned flanges *b* have their inner edges inclined slightly upward toward the arch and engaging the shoulders of the studs 75 B', with the result that the resilient metal locking strip presses downward on the razor blade and automatically adapts itself to varying thicknesses of the blade, and always holds the blade firmly in place on the combined 80 guard and support.

E represents the handle which may be of any suitable construction, and is hinged to the part A in the usual way.

To assemble the parts, the holder A being 85 in the position shown in Fig. 2, the razor blade is put in place, engaging the studs B and B', and then the sliding locking piece is slid longitudinally from the end of the support to engage the flanges on the studs 90 B and B'. The beveled ends *d'* of the in-turned flanges *d* will serve to center the locking piece so that it may be quickly slid into place.

To disassemble the parts, simply slide the 95 locking piece in the opposite direction, until it is disengaged from the two studs B and B', and then remove the razor blade.

It will be seen that the device is of such construction that it may be readily cleaned 100 when desired, and that the razor blade may be quickly applied or removed; thus the device consists essentially of three parts,—the support carrying the locking studs, the razor blade, and the sliding locking piece 105 for holding the blade firmly in position.

The locking piece should be made of resilient material so that it will automatically

press down on the razor blade and stiffen same near its edges, as well as hold same firmly in place.

Having thus described my invention, what 5 I claim and desire to secure by Letters Patent of the United States is:—

1. In a safety razor, the combination with a holder provided with a plurality of flanged studs projecting from one side thereof, of 10 a blade adapted to slip over said studs, and a sliding resilient locking piece arch-shaped in cross section and having the edges turned inward and slightly upward toward the arch, said member being, adapted to engage said flanged studs and to press down and hold the razor blade in position, substantially as described.
- 15 2. In a safety razor, the combination with

a holder provided with a plurality of flanged studs projecting from one side thereof, of a blade adapted to slip over said studs, and a sliding resilient locking piece arch-shaped in cross section and having the edges turned inward and slightly upward toward the arch, the said inwardly-turned portions 20 having beveled ends adapted to engage said flanged studs and to press down and hold the razor blade in position, substantially as described.

In testimony whereof, I affix my signature, in presence of two witnesses.

HOOPER COYNE.
